[57] CLAIM

The ornamental design for a portable power supply unit with AC-DC converter, as shown and described.

DESCRIPTION

FIG. 1 is a front and right side perspective view of a portable power supply unit with AC-DC converter showing our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The rear surface of the unit forms no part of the claimed design.

The portable power supply unit with AC-DC converter of our new design is a portable power supply unit for converting AC power to DC power and supplying DC power to, for example, an arc welder or a plasma arc cutter.
